SEWER CONSTRUCTION

George E. Bradbeer, Los Angeles, Calif.

Application December 1, 1934, Serial No. 755,580

13 Claims. (Cl. 182—1)

This invention relates to an improved sewer construction which eliminates the destructive effects of gases.

The general object of the invention is to provide a gravity sewer system so constructed that gases will not destroy the sewer conduit.

The fundamental principle of my invention is to provide means to obstruct or check the flow of sewage in its normal channel without reducing the normal capacity flow of the sewer, but causing the level of the sewage upgrade from the obstruction to rise and completely inundate and submerge the internal surface of the conduit to any predetermined point or elevation, thus eliminating the gases and consequent deterioration.

Another object of the invention is to provide a sewer system including novel means built into the sewer to prevent the sewer gases from harming the conduits.

20 A further object of the invention is to provide a sewer system including means to retain the sewer conduits completely full at all times.

Other objects and the advantages of this invention will be apparent from the following description taken in connection with the accompanying drawing wherein:

Fig. 1 is fragmentary central vertical section through a sewer system embodying the features of my invention;

30 Fig. 2 is a view similar to Fig. 1 showing a modified form of construction;

Fig. 3 is a section taken on line 3—3 of Fig. 2; and,

Fig. 4 is a section taken on line 4—4 of Fig. 2.

35 My improved construction is adaptable for use in sewers regardless of the kind of material of which they are composed or constructed and although in the following description I have shown my invention as embodied in a sewer system indicated generally at 10, it will be understood that this is merely indicant of one type of installation.

As shown the system 10 comprises a conduit 12 having a plurality of manholes or chambers 13 interposed therein. My improved construction as shown is particularly adaptable to large trunk lines wherein the conduit 12 may be jointed concrete or vitrified clay pipe or monolithic, but it will be understood that my invention is of general application and is not limited in its scope or application.

The manholes 13 may be of standard construction with the addition of vertical partitions or dams 15, of any desired type, which as shown are located at each manhole and extend upward from

the bottom of the manhole and across the manhole at an angle to the conduit 12. As is customary the conduit 12 is on a grade to provide gravity flow.

Standard stubs, 16, chimneys 17 or any other type of inlet connections may be provided along the conduit 12 if and where desired. The dams or obstructions 15 are preferably of a height so that the normal flow of sewage thereover causes a head which backs up the sewage sufficiently to inundate the conduit to the next higher chamber or manhole. As shown the dams 15 are of a height equal to or slightly higher than the level of the top of the conduit 12 where it opens, as indicated at 18, into the next manhole upgrade 15 and sufficient space is arranged for above the top of the dam to permit maximum sewer flow. The height of the obstructions may be varied to back up the sewage to any predetermined point or elevation to thereby retard the sewage and inundate 20 the conduit. Thus when sewage is admitted to the system 10 it flows through the conduit 12 to the first manhole 13 where the dam 15 restricts passageway therethrough until the sewage rises to the top of the dam. When the sewage reaches the top of the dam 15 the portion of the conduit 12 upgrade therefrom is completely filled with sewage and thus no gases can form and be disengaged in the conduit.

As additional sewage flows into the manhole 30 it passes over the dam and flows through the conduit 12 to the next manhole where it is again stopped by the dam 15 therein until the level of the sewage rises to the top of the dam. The manholes provide a vent so that there is no pressure or siphon action or anything to limit the normal flow. Thus in a sewer system embodying the features of my invention the conduit 12 between each manhole is at all times completely filled with sewage thereby preventing the formation and release of gases in the conduit 12.

In Figs. 3, 4 and 5, I have indicated a modified type of sewer system, embodying the features of my invention, generally at 20. The system 20 is similar to that shown in Fig. 1 and like portions thereof are indicated by similarly primed reference numerals. In the system 20, the dam 15' has an aperture 21 therein adjacent the intersection of the dam and bottom of the manhole. To control passageway through the aperture 21 45 I provide a gate valve 22 which may be of any desired construction and includes an operating member 23. In operation the gate valve 22 may be opened fully or partially to regulate the amount of sewage passing through the aperture 50 55

21. Adjacent the manhole 13' I provide a shunt conduit 24 one end of which opens into the conduit 12' upgrade from the manhole as indicated at 25 and the opposite end of the shunt conduit opens into the conduit downgrade from the manhole, as indicated at 26.

22. Adjacent the end 25 of the shunt conduit 24 I provide a small chamber or manhole 27 through which the conduit 24 passes. In the manhole 27 I provide a gate valve 28 which may be located where desired in the conduit 24 and which controls passage through the conduit. The valve 28 like the valve 22 may be of any desired construction and includes an operating member 29. When it is desired to work in the manhole 13' the gate valve 28 is opened to allow free passageway through the shunt conduit 24 whereupon the sewage upgrade from the shunt conduit flows through the shunt conduit around the manhole 13' and back into the conduit 12' downgrade from the manhole. When the shunt conduit 24 is used the aperture 24 in the dam 15' may be omitted and the gate valve 28 opened a slight distance to allow a portion of the sewage to pass through the shunt conduit 24 so that the manhole will not be filled.

23. With my invention the sewer is maintained at capacity by the use of the dams or similar barriers which are arranged at such location or locations as conditions and good engineering may require.

24. If desired the exposed portions which will not be submerged under the flow of sewage, such as the manhole wall 18' above the portion 18 and the lower face 15' of the dam 15, may be made of or covered with vitreous material.

25. From the foregoing description it will be apparent that I have provided a sewer system of novel construction which prevents formation and release of gases in the sewer conduits.

Having thus described my invention, I claim:

26. 1. In a gravity sewer system, a length of conduit, said conduit being arranged on a grade, means in said conduit to retard the flow therein, said means being disposed so that the normal flow of sewage thereover causes a head which backs up the sewage sufficiently to inundate the entire length of conduit above the obstruction, and means to vent the conduit.

27. 2. In a gravity sewer system, a conduit, said conduit being arranged on a grade, an enlarged chamber interposed in said conduit, a partition in said chamber extending thereacross, said partition being arranged and disposed to obstruct normal flow of sewage causing level of same, upgrade, to rise until it can flow over top or crest of partition, thus submerging interior of conduit, upgrade from partition to a point or elevation equal in height or elevation to the crest or top of flow over partition, space over partition to be vented to surface of ground to prevent either pressure or siphon effect.

28. 3. In a sewer system, a conduit, said conduit being arranged on a grade, an enlarged chamber interposed in said conduit, a partition in said chamber extending thereacross, said partition extending upward in said chamber, said partition being of a height so that the normal flow of sewage thereover causes a head which backs up the sewage sufficiently to inundate the portion of the conduit above the chamber.

29. 4. In a sewer system, a conduit, said conduit being on a grade, a plurality of chambers interposed in said conduit, and a valved partition in each of said chambers, said partitions being of a height so that the normal flow of sewage thereover causes a head which backs up the sewage sufficiently to inundate the portion of the conduit above the chamber, said partition

sufficiently to inundate the conduit to the next higher chamber.

30. 5. In a sewer system, a conduit, said conduit being arranged on a grade, a plurality of enlarged chambers interposed in said conduit, and a partition in each of said chambers extending thereacross at an angle to said conduit, said partitions being of a height so that the normal flow of sewage thereover causes a head which backs up the sewage sufficiently to inundate the conduit to the next higher chamber.

31. 6. In a sewer system, a conduit, said conduit being arranged on a grade, an enlarged chamber interposed in said conduit, a partition in said chamber extending thereacross, said partition being of a height so that the normal flow of sewage thereover causes a head which backs up the sewage sufficiently to inundate the portion of the conduit above the chamber, said partition having an aperture and adjustable means to control passage through said aperture.

32. 7. In a sewer system, a conduit, said conduit being arranged on a grade, a plurality of enlarged chambers interposed in said conduit, and a partition in each of said chambers extending thereacross at an angle to said conduit, said partitions being of a height so that the normal flow of sewage thereover causes a head which backs up the sewage sufficiently to inundate the conduit to the next higher chamber, each of said partitions having an aperture and movable means to control passage through said apertures.

33. 8. In a sewer system, a conduit, said conduit being arranged on a grade, a plurality of chambers interposed in said conduit, a partition in each of said chambers extending thereacross at an angle to said conduit, said partitions being of a height so that the normal flow of sewage thereover causes a head which backs up the sewage sufficiently to inundate the conduit to the next higher chamber, a shunt conduit adjacent each of said chambers, one end of said shunt conduits opening into said conduit upgrade from its associated chamber and the opposite end opening into said conduit downgrade from its associated chamber, and adjustable means adjacent the upgrade ends of said shunt conduits to control passage through said shunt conduits.

34. 9. In a sewer system, a conduit, said conduit being arranged on a grade, a plurality of enlarged chambers interposed in said conduit, a partition in each of said chambers extending thereacross at an angle to said conduit, said partitions being of a height so that the normal flow of sewage thereover causes a head which backs up the sewage sufficiently to inundate the conduit to the next higher chamber, each of said partitions having an aperture, movable means to control passage through said apertures, a shunt conduit adjacent each of said chambers, one end of said shunt conduits opening into said conduit upgrade from its associated chamber and the opposite end opening into said conduit downgrade from its associated chamber, and adjustable means adjacent the upgrade ends of each shunt conduit to control passage through said shunt conduits.

35. 10. In a sewer system, a conduit, said conduit being arranged on a grade, an enlarged chamber interposed in said conduit, a partition in said chamber extending thereacross, said partition being of a height so that the normal flow of sewage thereover causes a head which backs up the sewage sufficiently to inundate the portion of the conduit above the chamber, said partition

having an aperture and adjustable means to control passage through said aperture, a shunt conduit adjacent said chamber, one end of said shunt conduit opening into said conduit upgrade from 5 said chamber and the opposite end opening into said conduit downgrade from said chamber, and adjustable means to control passage through said shunt conduit.

11. In a gravity sewer system, a conduit comprising a plurality of connected lengths, each 10 length having an inlet portion and an outlet portion, said outlet portion including a part over which sewage flows, said part being of a height so that a normal flow of sewage thereover causes 15 a head which backs up the sewage sufficiently to entirely inundate the length of conduit above the said part.

12. In a gravity sewer system, a conduit laid on a grade and comprising a plurality of connected lengths, each of said lengths having an inlet portion and an outlet portion and obstructing means in each of said lengths, said obstructing 5 means being disposed at a location to maintain the fluid in the length directly above the obstructing means at a level whereby it completely fills the length.

13. The method of eliminating the destructive 10 effects of gases upon the walls of sewers comprising providing a conduit including a plurality of lengths and maintaining the sewage in each length under a head which backs up the sewage a sufficient distance to completely inundate the 15 length.

GEORGE E. BRADBEER.
